ELEVATOR SYSTEM

Frank Louis Kebelman, Rockville Centre, N. Y.,
assignor to Otis Elevator Company, New York,
N. Y., a corporation of New Jersey

Application August 27, 1936, Serial No. 98,111

4 Claims. (Cl. 177—336)

The invention relates to elevator systems.

In certain types of elevator installations, such as those for handling freight, service demands are not as frequent as in other types. Such installations do not require elaborate methods of control and may be of relatively low car speed. These and other factors contribute to minimizing the cost of the installation.

Various simplified controls have been provided for such installations. Among these are systems in which the users and prospective users of the car control the operation of the car themselves. Push buttons are provided at the landings and in the car for controlling the starting and stopping of the car. These push buttons are arranged to control the operation of the car directly, dispensing with floor relays or equivalent devices and thus effecting considerable saving. With such control, the user maintains the push button depressed until the desired landing is reached. It is desirable and the usual practice that the hatchway doors of such installations be of the solid type. Vision panels have been provided in these doors in order that the prospective users at the landings may judge the position of the car in controlling the stopping of the car. The invention is especially directed to elevator systems of this character.

The principal object of the invention resides in the improvement of such elevator systems.

One feature of the invention is to stop the car automatically at the landing at which a push button is depressed.

Another feature of the invention is to signal the arrival of the car to the prospective user as the stop is made so that the push button may be released.

With these features embodied in an elevator system of the above character, the vision panels in the hatchway doors may be omitted, decreasing the cost of the installation as well as providing improved operation.

In carrying out the invention, according to the embodiment to be described, a push button is located at each landing for operation by the prospective users to call the car. A signal lamp is also located at each landing for advising the prospective user of the arrival of the car. An up push button and a down push button are provided in the car for operation by occupants of the car to send the car to the desired destination. Another signal lamp is located at each landing for advising prospective users when the car is in motion. The control apparatus is so arranged that, upon a push button at a landing being depressed, the "car

moving" light at each landing is illuminated and the car is started toward the landing at which the push button is located. Upon the arrival of the car at the landing, it is brought to a stop automatically. Incident to the stopping operation, the "car moving" lights are extinguished and the "car here" light at the landing at which the stop is being made is illuminated, advising the prospective user that the push button may be released. Should the car be positioned at the landing at which the push button is pressed, the "car here" light at the landing is lighted immediately, indicating that the car is at the landing. When the car is at a landing or has been brought to the landing, the prospective user may enter the car and press the push button for the direction in which his desired destination lies. Upon the arrival of the car at the landing desired, the push button is released and the car is brought to a stop.

A general idea of the invention, the mode of carrying it out which is at present preferred, and various features and advantages thereof can be gained from the above statements. Other features and advantages of the invention will be apparent from the following description and appended claims.

In the drawings:

Figure 1 is a simplified schematic representation of an elevator installation in accordance with the invention;

Figure 2 is a view of the front of a push button box at a landing;

Figure 3 is a diagrammatic representation of the control panel, showing particularly the relationship of the coils and contacts of the various electromagnetic switches mounted thereon; and

Figure 4 is a simplified wiring diagram of the power and control circuits; and

Figure 4a is a key sheet for Figure 4 showing the electromagnetic switches in spindle form with the contacts and coils arranged on the spindles in horizontal alignment with the corresponding contacts and coils in the wiring diagram.

For a general understanding of the invention, reference may be had to Figure 1, wherein various parts of the system, chosen to illustrate the principles of the invention, are indicated either by reference characters or by legends. The elevator car is raised and lowered by means of a hoisting motor. This motor drives a traction sheave over which pass the hoisting ropes for the car and counterweight. An electromechanical brake is provided and is applied to effect the final stopping operation and to hold the car when at rest.

Mechanism actuated in accordance with car movement is utilized in carrying out the invention. This mechanism has been illustrated as comprising a plurality of floor stop switches in the hatchway, one for each landing. Each switch is provided with a roller which is operated by a slotted cam 166 carried by the car. When the car is stopped at a floor as illustrated, the operating arm of the switch upon which the roller is mounted is in neutral position. When the car leaves a floor in the upward direction the cam moves the arm into an operative position on one side of neutral, and when the car leaves the floor in the down direction the cam moves the arm to the corresponding operative position on the other side of neutral. As the car arrives at a floor, the operating arm of the switch for that floor is moved from operative position to neutral, causing the opening of the switch at slow down distance from the floor level. This causes the car to be brought to a stop at the floor level.

A push button, hereinafter termed "hall button", is provided at each landing to call the car. The "car here" light and "car moving" light for each landing are preferably associated with the push button in the same operating box. A front view of such arrangement is illustrated in Figure 2. The contacts of the push button are operated by means of a knob 158 which extends through an aperture in the face plate 156 for the box. The lights are arranged behind jewels 157 and 158 provided in the face plate. These jewels are preferably of distinctive colors, such as red for the "car moving" light and green for the "car here" light. These lights may also be marked "Car here" and "Car moving" as indicated. The push buttons in the car are designated "Up" and "Down", the "Up" push button being operated to cause upward travel of the car and the "Down" push button being operated to cause downward travel of the car. An emergency stop button 38 is also provided in the car.

A horizontally sliding car gate and hatchway doors of the bi-parting vertically sliding type have been illustrated. Mechanism has also been illustrated for locking the hatchway doors in closed position. This mechanism is the same for each door and comprises a bell crank lever 167, one arm of which cooperates with a catch 168 on the door 50 to latch the door against opening. The other arm of the lever is provided with an operating roller 167. The roller is adapted to be engaged by a retiring cam 168 carried by the car to move the lever out of the path of movement of the catch on the door, permitting the door to be moved to open position. The cam is retracted by means of a magnet 122 carried by the elevator car.

Reference may now be had to Figure 4, which illustrates diagrammatically the various control and power circuits. No attempt is made in this figure to show the coils and contacts of the electromagnetic switches in their associated positions, a "straight" or "across line" diagram being employed. In this type of diagram the coils and contacts of the switches are separated so as to make the connections to the supply lines as simple and direct as possible. The numerals employed in designating the various elements in the circuits are arranged in sequence, the lowest numeral, 11, which indicates one blade of the main line switch, occurring in the upper left hand corner of the figure. The succeeding numbers follow in numerical sequence from left to right downwardly of the sheet of drawings.

The circuits are illustrated for five floors. It is

to be understood, however, that the invention is applicable to installations of other numbers of floors. The invention is applicable to installations having either direct current or alternating current power supply. A three-phase alternating current power supply has been illustrated in which the supply mains are designated I, II and III. The blades of the main line switch for connecting the system to the supply mains are designated 11, 13 and 14.

The elevator hoisting motor is shown as a three-phase squirrel cage induction motor. The rotor of this motor is designated 138 and its stator windings 131, 133 and 134. The release coil of the electromechanical brake is designated 126. Two sets of door contacts are illustrated, those of one set being closed when their respective doors are closed and the others being closed only in the event that their respective doors are closed and locked. The contacts of each set are arranged in series relation and are represented on the diagram by a single set of contacts. Those which are closed when the doors are closed are designated 33 and are termed "door sequence contacts", while those which are closed only when the doors are closed and locked are designated 41 and are termed "door lock contacts". The gate contacts are designated 40. Door lock contacts are indicated in Figure 1 but door sequence and gate contacts are not shown in that figure as their arrangement is well understood. The contacts of the various safety devices have not been illustrated in the interests of simplicity.

The up push button in the car is designated 37 and the down push button in the car is designated 42. The hall buttons are designated 112, 98, 83, 71 and 57 for the first to the fifth floors respectively. The floor stop switches are designated 114, 86, 84, 72 and 50 for the first to the fifth floors respectively. The "car here" lights are designated 118, 102, 90, 76 and 64 for the first to the fifth floors respectively and the "car moving" lights are designated 20, 21, 22, 23 and 24 for the first to the fifth floors respectively.

The floor stop switches are illustrated diagrammatically in Figure 4. The switches for intermediate floors are of the same construction. Each switch comprises a pair of bridging contacts for cooperating with three stationary contacts and a pair of making contacts biased to engaged position but maintained separated mechanically when the car is away from the floor for which the switch is provided. When the car is at an intermediate floor, the floor stop switch operating cam on the car has engaged the roller of the floor stop switch 55 for that floor and moved the operating arm to neutral. In this position, the bridging contacts are disengaged from the stationary contacts and the making contacts are released so that they are in engagement. This is the position of the parts 60 of the third floor stop switch 84, the circuits being shown for the condition where the car is stopped at the third floor. The bridging contacts 81 and 85 are disengaged from stationary contacts 88, 82 and 86 and the making contacts 87 are engaged. 65 The car being above the second floor, the floor stop switch for that floor is in position where its bridging contacts 83 and 87 engage contacts 82 and 84 and its making contacts 101 are mechanically held in separated condition. Similarly, the car 70 being below the fourth floor, the floor stop switch for that floor is in position where its bridging contacts 87 and 74 engage contacts 70 and 73 and its making contacts 75 are mechanically held in separated condition. The floor stop switches for the 75

terminal floors are of the same construction except that the uppermost stationary contact of the upper terminal floor stop switch and the lowest stationary contact of the lower terminal stop switch are omitted as in normal operation these switches are not moved beyond neutral position from the position illustrated.

A transformer having a primary winding 12 and a secondary winding 15 is connected across supply mains I and II to provide the desired voltage for operating the electromagnetic switches. Assuming 220 volt electromagnetic switches, in order that 110 volt lamps may be used the circuit for the "car moving" lamps is taken from the midpoint of the secondary winding 15 of the transformer, while a voltage regulating resistance 60 is provided for the "car here" lamps.

The electromagnetic switches have been designated as follows:

- 20 AN—Auxiliary non-interference switch
- D—Down direction switch
- DC—Door contact relay
- N—Non-interference switch
- 25 P—Potential switch
- T—Time switch
- U—Up direction switch

Throughout the description which follows, these letters, in addition to reference numerals, will be applied to parts of the above designated switches. For example, coil U53 indicates that the coil is provided for the up direction switch. In a similar manner the coil of the retiring cam magnet is designated CM122. The relationship of the coils and contacts of the switches may be seen from Figure 3, where the switches are arranged, in so far as practical, in alphabetical order. The relationship of these coils and contacts may also be seen from Figure 4a where these switches are arranged in alphabetical order and are shown in spindle form. The positions of the coils and contacts in the wiring diagram may be found by referring to Figure 4a where the coils and contacts are positioned on the spindles in horizontal alignment with the corresponding elements of the wiring diagram. Thus, by first locating any coil or contact on the spindle diagram, the corresponding element of the wiring diagram may be readily found. The switches are illustrated in Figure 4 50 in deenergized condition.

Assume that the car is standing idle at the third floor with the hatchway door and car gate closed, the circuits being illustrated in accordance with this assumption. Under such conditions, door sequence contacts 33 are in engagement, connecting coil DC34 of the door contact relay across the secondary winding 15 of the transformer. This relay is therefore operated, separating its contacts DC35, and maintaining coil T31 of the time switch deenergized.

Assume further that the use of the car is desired at the fifth floor. Upon the prospective user pressing the fifth floor hall button 57, a circuit is completed through contacts T123 for coil CM122 of the cam magnet to retract the retiring cam, locking the hatchway door at the third floor. This causes the engagement of door lock contacts 41, completing a circuit for coil U53 of the up direction switch. This circuit is from the left hand side of the secondary winding 15 of the transformer through emergency stop button 30, door lock contacts 41, contacts 45 and 51 of the floor stop switch for the fifth floor, 70 coil U53, contacts D54, contacts N55, contacts

T56, hall button 57, and gate contacts 40, to the other side of winding 15.

The up direction switch, upon operation, engages contacts U16, completing a circuit for the "car moving" lights 20, 21, 22, 23 and 24 at the 5 respective floors. The lighting of this light at the fifth floor advises the prospective user that he has obtained control of the car. The lighting of these lights at other floors advises later prospective users at these floors that the car is in use. The up direction switch also separates its interlock contacts U109 in the circuit for coil D108 of the down direction switch. It engages contacts U124 and U127, preparing circuits for the stator windings of the elevator hoisting motor for upward 15 car travel and for the brake release coil. It also engages contacts U46, completing a circuit through the fifth floor stop switch for coil P47 of the potential switch.

The potential switch, upon operation, engages 20 contacts P116 and P121, completing the circuits for the stator windings of the elevator hoisting motor and the brake release coil. This causes the brake to be released and the car to be started in the up direction.

The potential switch also separates contacts 25 P61 in the circuit common to the "car here" lights. These contacts are provided to prevent the lighting of a "car here" light at a floor when as the car passes the floor. It engages contacts P63, P113 and P119 in parallel with contacts T56, T111 and T123 respectively. It also engages contacts P27 to effect the energization of coil T31 of 30 the time switch, causing the separation of contacts T56 and T111. The separation of contacts T56 is without effect as coil U53 is maintained energized through contacts P63.

By maintaining the fifth floor hall button de- 40 pressed, the car is caused to continue in operation until it arrives at a certain distance from the fifth floor. When this point is reached, the floor stop switch for the fifth floor is moved into position disengaging its bridging contacts from stationary contacts 45 and 51. This deenergizes 45 coil U53 of the up direction switch and coil P47 of the potential switch. The resultant separation of contacts P116, P121, U124 and U127 causes the deenergization of the stator windings of the elevator hoisting motor and of brake release coil 50 P126, causing the brake to be applied to bring the car to a stop at the fifth floor landing.

The separation of contacts U16 breaks the circuit for the "car moving" lights. The reengagement of contacts P61 together with the engagement of making contacts 62 of the fifth floor stop switch as the car comes to a stop completes the circuit for "car here" light 64 at the fifth floor. This light is thereupon illuminated, advising the prospective user of the arrival of the car at the floor. Thus he may release the hall button. The release of the hall button breaks the circuit for the "car here" light at the fifth floor and also for coil CM122 of the retiring cam magnet. This magnet permits the retiring cam to be extended 60 to unlock the door and effect the separation of door lock contacts 41.

The car cannot be operated by hall buttons after the "car moving" lights are extinguished and the stop has been made, owing to contacts P63 and P113 being separated. Contacts P63, P113 and P119 separate to open the by-pass circuits across time switch contacts T56, T111 and T123 respectively at the same time that contacts P27 separate to deenergize coil T31 of the time 75

switch. The time switch is delayed in dropping out to reengage its contacts, thereby providing a certain time interval after the stop is made in which the pressing of a hall button at another floor cannot establish a circuit for the coil of a direction switch to start the car or establish a circuit for coil CM122 of the retiring cam magnet to prevent the unlocking of the hatchway door. Thus a time interval is provided for the hatchway door and car gate to be opened without the possibility of interference.

The opening of the hatchway door and car gate causes the separation of door sequence contacts 33 and gate contacts 40 respectively. The separation of contacts 33 breaks the circuit for coil DC34 of the door contact relay, which drops out to reengage contacts DC35. This reestablishes the circuit for coil T31 of the time switch, maintaining contacts T56, T111 and T123 separated. Upon the prospective user entering the car and the closing of the hatchway door and car gate, gate contacts 40 and door sequence contacts 33 reengage. The reengagement of contacts 33 reestablishes the circuit for coil DC34 of the door contact relay, which operates to separate contacts DC35, again deenergizing coil T31 of the time switch. Thus time is provided for the occupant of the car to press the button to start the car toward his desired destination without the possibility of interference from hall buttons.

Assume that the occupant of the car desires the car to travel to the second floor. To effect such operation, he presses down button 42 in the car. This completes a circuit for coil AN38 of the auxiliary non-interference switch. This switch operates to engage contacts AN25 to complete a circuit for coil N28 of the non-interference switch. The non-interference switch operates to engage contacts N32, establishing a self-holding circuit, and to separate contacts N55 and N110 in the circuits from the hall buttons to the coils of the direction switches. The auxiliary non-interference switch also engages contacts AN120 to complete a circuit for coil CM122 of the retiring cam magnet, attracting the retiring cam to effect the locking of the fifth floor hatchway door and the reengagement of door lock contacts 41. This completes a circuit for coil D108 of the down direction switch. This circuit is through emergency stop button 38, door lock contacts 41, contacts 104 and 107 of the floor stop switch for the first floor, coil D108, contacts U108, down button 42 and gate contacts 40.

The down direction switch, upon operation, engages contacts D17 to complete a circuit for the "car moving" lights. It separates interlock contacts D54 in the circuit for coil U53 of the up direction switch and engages contacts D125 and D130, preparing the circuits for the stator windings of the elevator hoisting motor for downward car travel and for the brake release coil. It also engages contacts D106 to complete a circuit for coil P47 of the potential switch.

The potential switch engages contacts P116 and P121, completing the circuits for the stator windings of the elevator hoisting motor and brake release coil to effect the starting of the car in the down direction. The engagement of contacts P27 causes reenergization of the coil of the time switch.

The down button in the car is maintained depressed until the car arrives at its stopping distance from the second floor. When this point is reached the button is released, breaking the circuit for coil D168 of the down direction switch,

causing this switch to drop out to deenergize the hoisting motor and brake release coil. Thus the brake is applied to bring the car to a stop at the second floor landing. The separation of contacts D17 breaks the circuit for the "car moving" lights. The separation of contacts D108 breaks the circuit for coil P47 of the potential switch. The consequent separation of contacts P27 deenergizes coil T31 of the time switch.

The release of the down button also breaks the circuit for coil AN38 of the auxiliary non-interference switch, which drops out to separate its contacts AN25 and AN120. Coil N28 of the non-interference switch is maintained energized after the separation of contacts AN25 by contacts N32. The separation of contacts AN120 breaks the circuit for coil CM122 of the retiring cam magnet, releasing the retiring cam to unlock the second floor hatchway door. Thus the door and gate may be moved to open position to permit the occupant of the car to leave the car. The separation of gate contacts 40 upon the opening of the car gate breaks the circuit for coil N28 of the non-interference switch, causing the reengagement of contacts N55 and N110. The separation of door sequence contacts 33 upon the opening of the hatchway door deenergizes coil DC34 of the door contact relay, which reengages contacts DC35 to reenergize coil T31 of the time switch. Thus non-interference from the halls after the deenergization of the non-interference switch N is maintained by time switch T, contacts T56 and T111 of which are separated. Upon the reclosure of the car gate and hatchway door and the expiration of the time interval provided by the time switch, deenergized as a result of the reengagement of door sequence contacts 33 to effect the operation of door contact switch DC, the car may again be operated by hall buttons.

It is believed it will be understood from the above description that when the car is available for operation by hall buttons, it is started in the down direction in response to the pressure of a hall button for a floor below the one at which the car is positioned, and is started in the up direction in response to the pressing of a hall button for a floor above the one at which the car is positioned. In order that the circuits for the direction switch coils may be readily seen when the hall button is pressed for an intermediate floor, assume that with the car positioned at the third floor the fourth floor hall button 71 is pressed. This completes a circuit for coil U53 of the up direction switch through stop button 38, door lock contacts 41, the floor stop switch 58 for the fifth floor, coil U53, contacts D54, contacts N55 and contacts T56 as before, thence through contacts 73 and 70 of the floor stop switch for the fourth floor, push button 71, and gate contacts 40. Assume that instead of the fourth floor hall button the second floor hall button 85 is pressed. This completes a circuit for coil D168 of the down direction switch through stop button 38, door lock contacts 41, floor stop switch 114 for the first floor, coil D168, contacts U108, contacts N110, contacts T111, and thence through contacts 92 and 94 of the floor stop switch for the second floor, push button 85, and gate contacts 40. In either case, upon the arrival of the car at the floor at which the button 70 is pressed, it is automatically stopped and the "car here" light at that floor is illuminated.

If the hall button should be pressed at the floor at which the car is positioned, the car is not started and instead a circuit is established for the

"car here" light for that floor. The pressing of the third floor hall button 83 with the car at the third floor establishes a circuit for "car here" light 90 at the third floor through stop contacts 5 30, door lock contacts 41, resistance 60, contacts P61, contacts 87, light 90, push button 83, and gate contacts 40. The lighting of the "car here" light upon pressing of the button advises the prospective user that the car is already at that 10 floor.

It is believed that it will also be understood from the above description that the pressing of the up push button in the car under conditions where the car is at a floor below the fifth floor 15 causes the car to be started in the up direction and that the car continues to travel in the up direction until this button is released. When the occupant of the car desires to have the car travel to the terminal floor, he maintains the operated 20 button pressed until the terminal floor is reached and the stop is made by the opening of the floor stop switch for the terminal floor. When the car is to make a stop at an intermediate floor, the button is released as the car arrives at its 25 stopping distance from the desired landing. The floor stop switches for floors which the car must pass to travel to a destination have no effect upon the operation of the car upon being swung from one operative position to the other as the 30 car passes the floor, the circuit for the coil of the operated direction switch being maintained by the push button which is being held pressed.

Several of the control features illustrated are in the nature of refinements and may be omitted 35 if not desired for a particular installation. This may include time switch T, contacts P63, P113 and P119 by-passing the time switch contacts, and the control for the time switch involving door sequence contacts 33, door contact relay DC 40 and contacts P21. The non-interference switch N and its control may be omitted or replaced by a manually operable non-interference button in the car connected in the place of contacts N55 and N110. The door lock contacts 41 may be 45 replaced by door sequence contacts. The retarding cam and its operating magnet and the control for the magnet may be omitted, particularly where the door lock contacts are omitted. This includes the omission of not only contacts 50 AN120 but also one pair of contacts of each hall button, permitting single contact hall buttons to be used. Contacts P61 of the potential switch may also be omitted. Where no car gate is provided, gate contacts 40 are omitted.

By way of a resume, it will be seen that in accordance with the principles of the invention, the car may be called from a floor to any other floor by pressing a single hall button at the calling 55 floor. If the calling floor is above the floor at 60 which the car is positioned, the car starts automatically in the up direction, and if it is below the floor at which the car is positioned the car starts automatically in the down direction. The hall button is maintained pressed until the car 65 arrives at the calling floor, where it automatically stops. While the hall button is pressed, a "car moving" light is lighted at each floor, advising prospective users that the car is in use or is answering a call. When the car stops at the 70 calling floor, the "car moving" lights are extinguished and a "car here" light is illuminated at the floor at which the stop is made. This advises the prospective user that the car has arrived at the floor so that the button may be released and the hatchway door and car gate may 75

be opened. When the car is occupied, the occupant may send the car to the desired floor by pressing either an up button or a down button, depending upon the direction of the floor to which he desires to have the car travel. This button 5 is maintained pressed until the car arrives at the desired floor, whereupon it is released and the car is brought to a stop.

What is claimed is:

1. A control system for an elevator car comprising; a plurality of manually operable controls, one at each of a plurality of landings; means responsive to the operation of a control at a landing other than the one at which the car is positioned and the manual maintaining of said control operated for causing the car to travel to and stop at such landing; a plurality of signals, one at each of said landings; and means operable, when the control operated is the one at the landing at which the car is located, to give said signal at that landing to indicate that the car is already at the landing and, when the control operated is one at some other landing, to give said signal at such other landing as the car arrives at that landing to indicate the arrival of the car at the landing.

2. A control system for an elevator car comprising; a plurality of manually operable controls, one at each of a plurality of landings; means responsive to the operation of a control at a landing, other than the one at which the car is located, for starting the car toward the landing at which the control is located and for bringing it to that landing provided the control is maintained operated, the release of said control prior to the car arriving at a predetermined distance from such landing causing the car to come to a stop before the landing is reached; means responsive to the arrival of the car at said predetermined distance from said landing at which said operated control is located for causing the car to come to a stop at said landing; a signal at each landing; and means for causing the giving of the signal at the landing at which the stop is made as the car is stopped at that landing, advising the person operating said control at that landing that the control may be released.

3. A control system for an elevator car comprising; a plurality of push buttons, one at each of a plurality of landings; a plurality of signals, one at each of said landings; means responsive to the pressing of any one of said push buttons, other than the one at the landing at which the push button is located, and the manual holding of said push button depressed until said signal at the landing at which such push button is located is given for bringing the car from the landing at which it is located to the landing at which said push button is located; and means responsive to the arrival of the car at a certain distance from said landing for causing the car to come to a stop at said landing and for causing said signal at said landing to be given so that said push button may be released, said push button upon being released causing the giving of said signal to be discontinued.

4. A control system for an elevator car comprising; a plurality of push buttons, one at each of a plurality of landings; a plurality of signal lamps, one at each of said landings; means responsive to the pressing of any one of said push buttons, other than the one at the landing at which the car is positioned, and the manual holding of said push button depressed until said signal lamp at the landing at which the push

button is located is lighted for causing the car to travel to such landing; and means responsive to the arrival of the car at such landing for bringing the car to a stop and for causing said signal lamp at said landing to be lighted to indicate that the car has arrived at that landing so that said push button may be released, said

last named means acting when the push button at the landing at which the car is positioned is pressed to cause said signal lamp at that landing to be lighted to indicate that the car is already at the landing.

FRANK LOUIS KEBELMAN.
